United States Patent [19]

Takeda

[11] Patent Number: Des. 306,303

[45] Date of Patent: ** Feb. 27, 1990

[54] LAMINATING DEVICE FOR
IDENTIFICATION CARDS OR THE LIKE

D. 185,069 5/1959 Crowle et al. D15/199
D. 197,152 12/1963 Plantholt D16/246
D. 210,104 2/1968 Plantholt D16/246
D. 218,484 8/1970 Kuhns D15/146

[75] Inventor: Shigekazu Takeda, Tokyo, Japan

Primary Examiner—Nelson C. Holtje
Assistant Examiner—Jeffrey Asch
Attorney, Agent, or Firm—Wenderoth, Lind & Ponack

[73] Assignee: Fuji Plastic Kikai Kabushiki Kaisha,
Tokyo, Japan

[57] CLAIM

[**] Term: 14 Years

The ornamental design for a laminating device for identification cards, or the like, as shown.

[21] Appl. No.: 102,643

DESCRIPTION

[22] Filed: Sep. 30, 1987

[30] Foreign Application Priority Data

Apr. 2, 1987 [JP] Japan 62-12420
[52] U.S. Cl. D15/199; D14/146
[58] Field of Search D15/199, 146, 145;
D16/246
